UNITED STATES PATENT OFFICE.

CHARLES O. YALE, OF ROME, NEW YORK.

CASTING-MACHINE.

SPECIFICATION forming part of Letters Patent No. 373,629, dated November 22, 1887.

Application filed March 8, 1886. Renewed October 29, 1887. Serial No. 253,732. (No model.)

To all whom it may concern:

Be it known that I, CHARLES O. YALE, of Rome, in the county of Oneida and State of New York, have invented certain new and 5 useful Improvements in Casting Machines; and I do hereby declare that the following is a full, clear, and exact description of the invention, which will enable others skilled in the art to which it appertains to make and use the same, 10 reference being had to the accompanying drawings, and to the figures of reference marked thereon, which form part of this specification.

My invention relates to casting-machines; and it consists in the mechanism hereinafter 15 pointed out and claimed.

In the accompanying drawings, Figure 1 represents a plan view of my improved casting-machine. Fig. 2 is a vertical section on line *x x*, Fig. 1. Fig. 3 is a vertical section of 20 the hopper, taken on line *x x*, Fig. 1, representing the same detached from the machine. Fig. 4 is a longitudinal section view of my improved charging-valve. Fig. 5 represents an anode cast in my machine, with its electric 25 splines cast therein. Fig. 6 is an edge view of Fig. 5 on line *y y*. Fig. 7 is an edge view of the molds in position to receive the casting. Fig. 8 is a perspective view of the molds open, showing position of splines *o o* before casting. 30

In the accompanying drawings similar figures of reference refer to corresponding parts throughout the several views.

In constructing my improved casting-machine I provide two rings or circles, 1 and 2, 35 Fig. 1. The outer ring or circle, 2, is supported in a suitable frame and held stationary, and is somewhat larger than ring or circle 1, their respective sizes and shapes being graded Fig. 40 according to the purposes or molds to be used, having reference to their size. I preferably construct the smaller ring or circle of the angle-iron 4. (Shown in cross-section in Fig. 2.) The ring or circle 1 is mounted to be rotated on anti-friction rolls 3, supported on suitable 45 bearings, the angle-iron forming the movable circle resting on a succession of anti-friction rolls, forming a track on which the circle travels. Three or more of these rolls are preferably provided. It is quite obvious that these

anti-friction rolls may be attached to the moving ring or circle in such a manner as to travel on a track provided for them. It is equally obvious that either of said rings or circles may be constructed to move, one being held stationary. On one angle of the traveling ring or circle I attach a succession of jointed molds of the required shape and form. These molds are jointed at the lower end, the upper end being free to open when the same passes the pouring-point. The rings or circles are located eccentrically to each other, as indicated in Fig. 1, their eccentric location being determined by the thickness or condition of the molds. The traveling ring or circle to which the jointed molds are attached is intermittently moved by ratchets 6, engaged by pawl 7, driven by crank 8 when power is applied. The ratchets and crank should be constructed in reference to the size and number of the molds in 70 reference to the traveling ring or circle, as the traveling ring or circle is moved the distance of one mold at a time. A mold is brought into position for receiving the metal, as indicated at 9, Fig. 1. The metal is poured in hopper 10, Fig. 3, held over the mouth of the mold to guide and distribute the metal. As each mold advances to receive the charge of metal, it passes between anti-friction rolls 11 11, Figs. 1 and 2, which are kept to their 75 position by coil-springs surrounding the shank 12 12, Fig. 7. The shanks to these anti-friction rolls fit and move in boxes 13 13, Fig. 7, mounted in the frame, and by this mechanism the mold is held firmly while it is receiving the charge. For accurately guiding and holding the traveling ring or circle to its work I provide a system of guide-rolls, 14 14, located on either side of the traveling circle or ring. 80

For pouring the metal into the mold from the furnace I provide charger 15, Fig. 4, having openings 16, 17, and 18, though the latter, however, may be omitted. This charger is inserted in the furnace with the opening 16 in 95 the charger extending through the walls of the furnace to receive the molten metal, as indicated in Fig. 2. The discharge end 18 extends over the opening in the molds, a sufficient space being left between the two to 100

accommodate the hopper for conducting the metal into the mouth of the mold. For opening and closing apertures 16 and 17 in the charger I provide valves 19 and 19, rigidly held on stem 20. These valves are located on the stem with reference to openings in the charger, so that when the valve-stem is drawn out, as indicated in Fig. 4, the molten metal rushes into the chamber 21, which is of sufficient size to retain metal to fill one mold. The valves and stem are then moved inward, and the valve closing the aperture 16, and at the same time opening the aperture 17, thereby allows the molten metal to flow into the mold, which is then moved on and another moved into position. As the mold moves past the pouring-point the same is allowed to separate, as indicated in Fig. 8, when the casting is removed. The mold is prepared by introducing at the upper end of the mold the thin splines of electric conducting metal, $o o$, which are cast into the anode, and applying a solution of finely-divided carbon, when the mold is ready for receiving another casting, which work is performed while the ring or moving circle is being moved.

25 represents the ornamental depressions in the mold, and 26 the spline on the edges of the mold.

30 In the drawings the machine illustrated was constructed with reference to its use in casting lead-bullion anodes. The machine, however, is equally adapted for use in casting brass, copper, zinc, antimony, and similar metals where thin castings are required. In producing thin casting from any of the metals before named great trouble is encountered, as the metal rapidly chills, thus preventing a perfect casting. To overcome this difficulty 40 the mold must be free from all gases produced by heated metal in the mold, as a slight quantity of gas generated by the metal prevents the same from flowing, thereby producing an imperfect casting. To produce a perfect casting of the character described it is quite important to introduce into the mold the element of non-conductor of heat to prevent rapid chilling. At the same time means must be provided for facilitating the flow of the metal 45 in the mold. The troubles hereinbefore set forth are measurably overcome by forming molds 22, Fig. 8, from carbon.

50 In many instances it is desirable to use a metal mold, in which case I form a carbonated surface in the molds themselves by the use of a mixture of finely-divided carbon and alcohol or its equivalent, the solution being applied to the face of the molds with a brush or its equivalent. By the use of this mixture a 55 complete casting may be formed with very little difficulty.

What I claim as new, and desire to secure by Letters Patent, is—

1. In a casting-machine, two rings of unequal size eccentrically located with reference to each other, with jointed molds mounted

thereon, and means for moving one of said rings.

2. In a casting-machine, the combination of two rings of unequal size eccentrically located with relation to each other, one of said rings constructed of angle-iron in cross-section, jointed molds rigidly held to the angle-iron ring, and means for intermittently moving the ring with the molds attached. 75

3. In a casting-machine, the combination of two rings of unequal size eccentrically located with relation to each other, one of said rings constructed of angle-iron, jointed molds held to the angle-iron ring, and means for moving the ring with the molds attached. 80

4. The combination of the rings of unequal size eccentrically located with relation to each other, the jointed molds attached to one of said rings, and means for moving the same. 85

5. The combination, with the stationary ring, of the movable ring with jointed molds attached thereto, and means for intermittently moving the movable ring.

6. The casting-machine having two rings of unequal size eccentrically located with reference to each other, with jointed mold mounted on one ring, in combination with the anti-friction roll located and mounted to engage and press the parts of the molds together when the metal is being poured, and means for adjusting said rolls. 90

7. The combination of two rings of unequal size eccentrically located with reference to each other, one of said rings movable, with jointed molds mounted thereon, anti-friction rolls mounted to engage and press the parts of the mold together, and means for intermittently moving the ring and molds. 100

8. The combination of the jointed molds attached to a movable ring, a stationary ring of different diameter, the two eccentrically located with reference to each other for pressing the molds together when the metal is poured. 105

9. The combination of a movable ring eccentrically located with reference to a ring of a different diameter, carrying the jointed mold and having ratchet-teeth, a pawl for engaging the teeth, and a crank for moving the pawl. 115

10. The jointed molds attached to a movable ring moving in contact with a stationary ring of different size, the two eccentrically located, in combination with a charger located at the closing-point of the eccentric, the charger having openings at opposite ends, and two valves on a valve-stem for opening and closing the inlet and outlet, for the purposes stated. 120

11. A casting-machine having a rotating wheel or ring surrounded by a ring of larger diameter, the two being eccentrically located with relation to each other, and the jointed molds attached to the rotating ring or wheel, substantially as set forth. 125

12. The combination of two eccentric surfaces, one being provided with jointed molds 130

and means for moving the molds, substantially as set forth.

13. The combination of the rotating ring carrying jointed carbonated molds and the 5 stationary ring of larger diameter, the two being rotated eccentrically, substantially as set forth.

In witness whereof I have affixed my signature in presence of two witnesses.

CHARLES O. YALE.
